CLAIM

The ornamental design for an implantable access port, as shown and described.

DESCRIPTION

FIG. 1 is a perspective view of a first embodiment, lined for the color green, of an implantable access port of my new design;

FIG. 2 is a front elevational view, lined for the color green, of the implantable access port illustrated in FIG. 1;

FIG. 3 is a left side elevational view, lined for the color green, of the implantable access port illustrated in FIG. 1;

FIG. 4 is a top view, lined for the color green, of the implantable access port illustrated in FIG. 1;

FIG. 5 is a bottom view, lined for the color green, of the implantable access port illustrated in FIG. 1;

FIG. 6 is a rear elevational view, lined for the color green, of the implantable access port illustrated in FIG. 1;

FIG. 7 is a perspective view of a second embodiment, lined for the color purple, of the implantable access port of my new design;

FIG. 8 is a front elevational view, lined for the color purple, of the implantable access port illustrated in FIG. 7;

FIG. 9 is a left side elevational view, lined for the color purple, of the implantable access port illustrated in FIG. 7;

FIG. 10 is a top view, lined for the color purple, of the implantable access port in FIG. 7;

FIG. 11 is a bottom view, lined for the color purple, of the implantable access port illustrated in FIG. 7;

FIG. 12 is a rear elevational view, lined for the color purple, of the implantable access port illustrated in FIG. 7;

FIG. 13 is a perspective view of a third embodiment, lined for the color blue, of the implantable access port of my new design;

FIG. 14 is a front elevational view, lined for the color blue, of the implantable access port illustrated in FIG. 13;

FIG. 15 is a left side elevational view, lined for the color blue, of the implantable access port illustrated in FIG. 13;

FIG. 16 is a top view, lined for the color blue, of the implantable access port illustrated in FIG. 13;

FIG. 17 is a bottom view, lined for the color blue, of the implantable access port illustrated in FIG. 13;

FIG. 18 is a rear elevational view, lined for the color blue, of the implantable access port illustrated in FIG. 13;

FIG. 19 is a perspective view of a fourth embodiment, lined for the color grey, of the implantable access port of my new design;

FIG. 20 is a front elevational view, lined for the color grey, of the implantable access port illustrated in FIG. 19;

FIG. 21 is a left side elevational view, lined for the color grey, of the implantable access port illustrated in FIG. 19;

FIG. 22 is a top view, lined for the color grey, of the implantable access port illustrated in FIG. 19;

FIG. 23 is a bottom view, lined for the color grey, of the implantable access port illustrated in FIG. 19;

FIG. 24 is a rear elevational view, lined for the color grey, of the implantable access port illustrated in FIG. 19;

FIG. 25 is a perspective view of a fifth embodiment, lined for the color yellow, of an implantable access port of my new design;

FIG. 26 is a front elevational view, lined for the color yellow, of the implantable access port illustrated in FIG. 25;

FIG. 27 is a left side elevational view, lined for the color yellow, of the implantable access port illustrated in FIG. 25;

FIG. 28 is a top view, lined for the color yellow, of the implantable access port illustrated in FIG. 25;

FIG. 29 is a bottom view, lined for the color yellow, of the implantable access port illustrated in FIG. 25;

FIG. 30 is a rear elevational view, lined for the color yellow, of the implantable access port illustrated in FIG. 25;

FIG. 31 is a perspective view of a sixth embodiment, lined for the color orange, of the implantable access port of my new design;

FIG. 32 is a front elevational view, lined for the color orange, of the implantable access port illustrated in FIG. 31;

FIG. 33 is a left side elevational view, lined for the color orange, of the implantable access port illustrated in FIG. 31;

FIG. 34 is a top view, lined for the color orange, of the implantable access port illustrated in FIG. 31;

FIG. 35 is a bottom view, lined for the color orange, of the implantable access port illustrated in FIG. 31; and,

FIG. 36 is a rear elevational view, lined for the color orange, of the implantable access port illustrated in FIG. 31.

The broken lines shown in FIGS. 1-36 are included for the purpose of illustrating environmental structures only and form no part of the claimed design.
